UNITED STATES PATENT OFFICE.

WILLIAM ALEXANDER ALLAN, OF STOUFFVILLE, ONTARIO, CANADA.

COMBINED ENGINE AND TURBINE.

1,261,993.

Specification of Letters Patent. Patented Apr. 9, 1918.

Application filed August 20, 1917. Serial No. 187,277.

To all whom it may concern:

Be it known that I, WILLIAM ALEXANDER ALLAN, of the village of Stouffville, in the county of York, in the Province of Ontario, 5 Canada, have invented certain new and useful Improvements in Combined Engines and Turbines, of which the following is the specification.

My invention relates to improvements in 10 combined engines and turbines in which the turbine will act as an auxiliary to the engine making available a considerable part of the velocity and heat of the exhaust gas or steam from the engine for the purpose of 15 conversion into mechanical power thereby producing an increase of power, in which the turbine will also act as a muffler for the engine and take the place of the fly wheel and it consists essentially of the following 20 arrangement and construction of parts as hereinafter more particularly explained.

Figure 1, is a side view of a two cylinder engine showing my turbine construction connected thereto, such turbine construction 25 being shown in section.

Fig. 2, is a perspective view of the turbine.

Fig. 3, is a longitudinal section through Fig. 2.

Fig. 4, is a longitudinal section similar to Fig. 3.

In the drawings like letters of reference indicate corresponding parts in the various figures.

35 1 indicates the body of an engine, 2 and 3 the cylinders, 4 the exhaust pipe and 5 the crank shaft of the engine provided with cranks 6 and 7 connected by piston rods 8 and 9 to the pistons 10 and 11 co-acting 40 with the cylinders 2 and 3.

12 indicates a supplemental crank on the crank shaft 5. 13 indicates an air compressing cylinder provided with a piston 14 connected by a piston rod 14^x to the crank 12.

45 15 indicates a chamber preferably carried by the cylinders 2 and 3 and connected by a pipe 15^x to the top of the air compressing cylinder 13. 16 indicates a steam or exhaust gas chamber connected at its lower end at 50 17 to the exhaust pipe 4 and provided at its upper end with a nozzle 18 extending into the exterior nozzle 19 leading from and forming part of the chamber 15.

20 55 20 indicates the turbine casing, which is suitably supported and connected to the nozzle 19 so that the nozzle leads tangentially thereto.

21 and 21^x indicate blade carrying members carrying a circumferential series of blades 22 extending longitudinally of the 60 turbine parallel with the axis. 23 indicates a chamber located within the blades 22, the major portion of which is cylindrical in form and provided with a port 24 opposite the mouth of the nozzle 19. The wall of the 65 chamber below the port 24 is substantially S-shape in form, the portion 25 curving backwardly toward the port 24 and forming at its end a boss 26 through which a stationary supporting shaft 27 of the turbine extends. From this point the wall is provided with a backwardly curving portion 28 merging at its end in the cylindrical wall portion of the casing and at the end this chamber is provided with an end wall portion 29 forming 70 an opening 30 through which the exhaust steam passes. It will be understood that the boss 26 is keyed or otherwise suitably secured to the shaft 27 so as to hold the chamber 23 stationary. 75

The plate 21^x forming the end of the blade carrying member is provided with a central orifice 31. 32 indicates a series of radial blades extending between the central portion 20^x of the plate 21^x and the outer portion 21'. The supporting plate 21 is provided with a sleeve 33, which is journaled in a suitable bearing standard 34. The opposite end of the shaft 27 is secured in a bearing 35. 80

36 indicates a worm secured to the sleeve 33. 37 indicates a worm gear meshing therewith. 38 indicates a shaft, to the upper end of which the worm gear 37 is secured. 39 indicates a worm secured to the 85 lower end of the shaft 38 and 40 indicates a gear mounted upon the crank shaft 5 of the engine. 90

Having described the principal parts involved in my invention I will briefly describe the operation of the same. 100

Exhaust steam passes through the exhaust pipe 4 into the chamber 16 and simultaneously air is compressed in the cylinder 13 and forced into the chamber 15 so as to fill 105 the space around the chamber 16. This air is heated by the exhaust gases contained in the chamber 16 and is carried by such exhaust and by reason of its own compression through the nozzle 19 against the blades 22 110

thereby carrying the blades circumferentially, the gases and air exhausting through the port 24 into the center of the turbine formed by the chamber 23, such exhaust 5 gases and air being forced against the radial blades 32 thereby giving a second impulse to the turbine member.

The momentum given to the turbine by the impulse first upon the blades 32 and 10 then upon the blades 32 is transmitted by the sleeve 33, worm gear 36 and worm 37 to the shaft 38 which is in driving connection with the crank shaft 5 of the engine, through the worm 39 and worm gear 40 and 15 thereby acting as an auxiliary to the engine drive.

It will also be seen that the turbine being connected to the crank shaft of the engine acts as a fly wheel to steady the motion 20 thereof and the exhaust of the engine passing into the turbine, such turbine acting as a muffler rendering the engine comparatively noiseless.

From this description it will be seen that 25 I have devised a very simple form of engine, which is provided with an auxiliary turbine co-acting therewith and by which the exhaust gases of the engine are utilized for heating air to drive such turbine. It will, 30 of course, be understood that as the air and gases pass from the blades 32 into the center of the turbine that they are carried against the concaved portion of the wall 25 and are thereby directed backwardly so that they 35 strike the blades 32 in such a direction as to drive the turbine in the same direction as is done by the impact of the air upon the blades 22.

Although in this specification I have described with great particularity the essential 40 parts comprised in my invention it will, of course, be understood that I may make vari-

ous changes therein without departing from the spirit of my invention.

It may be further stated that the S-shaped 45 chamber may be made more S like if desired so as to form a duplicate curved chamber portion on the opposite side of the shaft 27, a port similar to the port 24 being located diametrically opposite the port 24. This 50 would double the capacity of the turbine without increasing its size.

What I claim as my invention is—

1. In a turbine, the combination with an outer and inner stationary casing spaced 55 apart, of revolubly mounted heads forming the ends of the casing, and a circumferential series of turbine blades carried by the heads and extending between the outer and inner casings, and means for conducting steam 60 radially inward through the inner and outer casings including radial fan blades and forming an auxiliary driving member.

2. The device of claim 1 with the addition of having the radial blades depending from 65 the periphery of the inner revoluble head.

3. In a turbine, a stationary outer casing having a peripheral inlet, a stationary inner casing also having a peripheral inlet and an end outlet, revoluble heads for the casing, 70 turbine members carried thereby and extending between the inner and outer casings, one of such heads having an open center, fan blades secured in such open center against the end outlet of the inner casing, and means 75 for changing the direction of travel of steam passing through the inlet of the inner and outer casings and between the turbine members into the interior of the inner casing as it travels against the fan blades.

WILLIAM ALEXANDER ALLAN.
